UNITED STATES PATENT OFFICE.

GEORGE HAROLD DUNN, OF OAK PARK, ILLINOIS, ASSIGNEE TO AMERICAN CAN COMPANY, OF NEW YORK, N. Y., A CORPORATION OF NEW JERSEY.

SUPPORT FOR TIRE CASINGS OR THE LIKE.

Application filed June 21, 1923, Serial No. 646,768. Renewed January 7, 1928.

My invention relates to holders, or supports, for annular articles, such as automobile tire casings, and has for a principal object the provision of an improved holder, or support, of this character which may be constructed of sheet metal and which is so formed as to firmly hold the casing, or other article, without causing any damage thereto.

A further object of the invention is the provision of an improved construction of this character which will facilitate the packaging of the parts for shipment.

A still further object is the provision of a simplified structure of this type which may be economically manufactured both from the standpoint of the materials used and the manufacturing operations required.

Other objects and advantages of the invention will be apparent as it is better understood from the following description, which, taken in connection with the accompanying drawings, discloses a preferred embodiment thereof.

Referring to the drawings,

Figure 1 is a perspective view of a support in which my invention is embodied, a tire casing being shown in dotted lines in the position in which it is held by said support; and

Fig. 2 is a transverse section thereof, showing the end members in elevation.

For the purpose of illustrating my invention, I have shown on the drawing two pairs of end rocker members 21, which are connected together by means of a side member 22, and which are so constructed as to cause them to grip and hold the tire by the mere positioning of the latter, as will hereinafter appear. The opposing members 21 are rounded at the bottom, as indicated at 23 and are extended and lap past each other to form extended rocking surfaces, and are pivotally connected at 24 by means of a rivet or other securing member. It will be noted that the point of pivotal connection is well toward the inner extremity of projections 25 formed in said members 21, so that said members are adapted to move about their pivotal axes under the weight of a casing 26 when the latter is positioned between the upper portions of said members and upon supporting flanges 27 formed thereon. Said members 21 are cut away above the projections 25 to form upwardly extending arms 28 and said flanges 27 are

formed upon said arms by bending the metal upon a line of bend 29. The members 21 are also provided with flanges 31 on the outer edge thereof, this formation serving to strengthen the structure and to provide means for facilitating the connection with the side member 22. Said flange 27 terminates at a point a considerable distance from the end of the projection 25, so that the upwardly extending arms 28 may be moved toward each other to an extent permitting the holding of a relatively small tire, or other annular member.

The member 22 is provided with end flanges 32, which are adapted to be secured to suitably spaced members 21 by means of screws 33, or in other desired manner. The flanges 31 rest against the inner side of the member 22, and the flanges 32 on said member are disposed on the outside of said end members 21, forming a right angle engagement resulting in a reinforced and rigid structure. It will be noted that, in the present instance, the member 22 is applied at only one side, but flanges 31 are also provided on the members 21 at the opposite side and serve to strengthen the structure, as well as to improve the appearance and limit the opening movement of said members when resting on the floor.

The member 22 may have an advertisement, of any suitable type, thereon and, since it is constructed of sheet metal, this may be readily provided by a lithographing process, or in other inexpensive manner. Said member is flanged inwardly at the bottom, as indicated at 34, and at the top, as indicated at 35. While I have shown only one connecting member, it will, of course, be manifest that another could be provided at the opposite side, if desired, by merely aperturing the opposite members 21 to receive bolts or screws 33. The invention, of course, is not to be considered as limited to any specific contour of the parts, except in so far as may be necessary to attain the objects stated. The use of sheet metal for the entire construction is of very great advantage, from the standpoint of economy of manufacture, and the arrangement of the parts, whereby they may be separated and packed in a flat box for shipping, is of distinct commercial importance. The provision of the supporting flanges 27 is a very great practical improvement, from the standpoint

of convenience and effectiveness in service, since it prevents cutting of the tires and overcomes a difficulty which has commonly been experienced with other devices of this 5 general type.

It is thought that the invention and many of its attendant advantages will be understood from the foregoing description, and it will be apparent that various changes may 10 be made in the form, construction and arrangement of the parts without departing from the spirit and scope of the invention, or sacrificing all of its material advantages, the form hereinbefore described being 15 merely a preferred embodiment thereof.

I claim:

1. A support for automobile tire casings and the like, having in combination two pairs of sheet metal rocker members formed 20 with rounded bottoms 23, said bottoms being extended past andlapping each other

to provide extended supporting and rocking surfaces, pivots uniting the lapped portions of the members, and side members bent inward to form end flanges 32 enclosing the 25 outer parts of the rocker members and fixed to and uniting said rocker members, said rocker members being bent inward to form longitudinally extended flanges 31 which lie against the inner faces of said side members. 30

2. A support for automobile tire casings and the like, comprising a side body member, a pair of pivotally connected end members at each end, one of which is secured to said side body member, said pivoted end 35 members having parts adapted to extend up about a tire casing and to clamp under the weight of the tire, said pivoted end members being of sheet metal and having laterally extending lips along the edges engaged by the tire casing. 40

GEORGE HAROLD DUNN.
